UNITED STATES PATENT OFFICE.

TADAUS LYBURIS AND PETE F. SMITH, OF HERRIN, ILLINOIS.

LONG-RANGE PROJECTILE.

Application filed August 10, 1920. Serial No. 402,729.

To all whom it may concern:

Be it known that we, TADAUS LYBURIS and PETE F. SMITH, citizens of the United States, residing at Herrin, in the county of Williamson, State of Illinois, have invented certain new and useful Improvements in Long-Range Projectiles; and we do hereby declare the following to be a full, clear, and exact description of the invention, such as 10 will enable others skilled in the art to which it appertains, to make and use the same:

This invention relates to new and useful improvements in projectiles and particularly to long range projectiles.

15 One object is to provide a novel and improved device of this character which has means for facilitating the steady flight of the device through the air.

Another object is to provide guiding 20 means for a projectile which obviates the use of the rifling of the barrel of the gun, together with the particular manner in which the guiding means are supported on the projectile.

25 Other objects and advantages will be apparent from the following description when taken in connection with the accompanying drawing.

In the drawing:

30 Figure 1 is an elevation of a projectile made in accordance with our invention.

Figure 2 is a vertical longitudinal sectional view through the projectile.

Figure 3 is an enlarged vertical trans- 35 verse sectional view taken on the line 3—3 of Fig. 2.

Figure 4 is a vertical sectional view taken on the line 4—4 of Figure 2, enlarged.

Figure 5 is a rear elevation of the projectile.

40 Figure 6 is an enlarged vertical trans- verse sectional view taken on the line 6—6 of Figure 2.

Referring particularly to the accompany- 45 ing drawing, 10 represents the elongated hollow body of the projectile, the rear end being of the same diameter as the intermediate portion, while the forward end is tapered to form the nose 11. Extending longitudinally through the body 10, and having its ends secured in openings 12 and 13, 50 formed respectively in the nose and butt ends

of the body, is a tube 14, and rotatably supported in this tube is a longitudinally extending shaft 15. Rotatably carried by the 55 forward end of the shaft, and disposed forwardly of the nose of the body, is a screw 16. Similarly mounted on the other end of the shaft, and disposed rearwardly of the butt end of the body, is a second longer 60 screw, this latter propeller being longer so that a more perfect balance of the body, during its forward flight through the air will be assured, said propeller being shown at 17.

65 The forward screw 16 is formed with a hub portion 18 which is received in a cup member 19 threadedly engaged in the nose of the body, and which bears against the circular series of ball bearings 20, disposed 70 in said cup member. The rear screw 17 is similarly provided with a hub portion 21 which engages the balls 22 disposed in the cup member 23 in the rear or butt end of the body. Surrounding the cup member 75 23 are the series of internally threaded openings 24 into which are engaged screw plugs 25. Through these openings, when the plugs are removed, the explosive is introduced into the interior of the body of 80 the projectile. The projectile is arranged to be placed in the outer open end of the shell 26, in the manner of the ordinary bullet of the common rifle shell, a wad 27 being disposed behind the rear screw 17, and in front 85 of the charge of explosive which is adapted to drive the projectile from the shell. A fuse 28 is disposed through one of the openings 24 and through a groove formed in one of the plugs 25. The inner end of the fuse 90 90 is disposed within the mass of explosive within the body of the projectile.

As the projectile proceeds through the air the screws 16 and 17 will rotate at a high rate of speed serving to keep the projectile 95 on an even keel while at the same time directing the same on its course. The rear screw 17 being longer than the front one will act in the manner of the feather of an arrow to more properly insure the direct 100 flight of the projectile.

What is claimed is:

A projectile comprising an explosive containing body, a tube disposed longitudinally

through the center of the body, a rotatable shaft disposed through the said tube, a conical screw mounted on the forward end of the shaft externally of the body, and a cylindrical screw mounted on the rear end of the shaft and externally of the body for sustaining the longitudinal balance of the body of the projectile.

In testimony whereof, we affix our signatures, in the presence of two witnesses.

TADAUS LYBURIS.
PETE F. SMITH.
